UNITED STATES PATENT OFFICE.

GLENN E. McFADDEN, OF DETROIT, MICHIGAN, ASSIGNOR TO LINCOLN MANUFACTURING COMPANY, OF DETROIT, MICHIGAN, A CORPORATION OF MICHIGAN.

DESIGN FOR A LIGHTING-FIXTURE CHANDELIER.

Application filed December 15, 1923. Serial No. 29,280. Term of patent 7 years.

To all whom it may concern:

Be it known that I, GLENN E. McFADDEN, a citizen of the United States, residing at Detroit, county of Wayne, State of Michigan, have invented a new, original, and ornamental Design for a Lighting-Fixture Chandelier, of which the following is a specification, reference being had to the accompanying drawing, forming part thereof.

Fig. 1 is a front elevation.

Fig. 2 is a plan view of the lamp portion alone along the line 2—2 shown in Figure 1.

Fig. 3 is a bottom plan view.

I claim:

The ornamental design for a lighting fixture chandelier, substantially as shown.
